**BIS-ADDITION PRODUCTS AND METHODS
OF PREPARING SAME**

Charles Kezerian, Los Angeles, and William M. Ramsey, Downey, Calif., assignors to Stauffer Chemical Company, a corporation of Delaware
No Drawing. Filed Mar. 18, 1959, Ser. No. 800,116
28 Claims. (Cl. 260—429)

This invention relates to products, and methods of producing same, from the group consisting of:

(a) A compound essentially of the formula:

wherein Z_1 and Z_2 are the same or different bis-adduction reaction residues of a member of the class consisting of unsaturated polycarboxylic acids and salts (includes acid addition salts and salts having a cation bonded to a carboxyl group) thereof and R_5 is the substituent defined below;

(b) Chelates comprising the product of (a) and a polyvalent metal ion; and

(c) Esters comprising the product of (a) and a lower alkyl substituent bonded to at least one carboxyl group.

Stated in a different manner, this invention relates to bis-adduction products, and methods of producing same, from the group consisting of:

(a) A compound essentially of the formula:

wherein R_5 is a member of the class consisting of alkylene, phenylene-lower alkylene-phenylene, lower alkylene-phenylene-lower alkylene, and lower alkylene-NH-lower alkylene groups; and R_2 and R_4 are members of the class consisting of hydrogen, lower alkyl groups, —COOB groups, and lower alkylene-COOB groups; R_1 and R_3 are members of the class consisting of lower alkylene groups and lower alkylene groups having an additional free bond; n is a positive integer of not less than 1 and not more than 2; R_6 and R_7 are lower alkylene groups when n is 1; R_8 and R_9 are members of the class consisting of hydrogen, lower alkyl radicals, and lower alkylene-COOB groups; and B in the above formula is the same or different radical from the class consisting of hydrogen, organic base radicals, inorganic base radicals, and lower alkyl radicals;

(b) Chelates comprising the compound of (a) and a polyvalent metal ion; and

(c) Salts (i.e., includes acid addition salts) of the compound of (a).

The term "alkylene" is herein intended to include alkyl and substituted alkyl radicals having an additional free bond. The terms "alkenyl," "alkyl" and "phenylene" are intended to include substituted alkenyl, alkyl and phenylene groups, respectively. The term "carboxyl" is herein intended to include the

2

group. The phrase "unsaturated polycarboxylic acids" is herein intended to include acyclic ethylenically unsaturated polycarboxylic acids, lower alkenyl polycarboxylic acids, salts thereof, and their anhydrides.

5 R_5 in the above formula may be a member of one of the following groups: an alkylene radical such as exemplified by ethylene, hexamethylene and 2-hydroxy-propylene; a phenylene-lower alkylene-phenylene radical such as methylenediphenylene; a lower alkylene-phenylene-lower alkylene radical such as xylene; and a

15 radical (a) that is repeated a desired (the term "desired" may be zero) number of times, (b) wherein each lower alkylene radical may be the same or different, and (c) wherein each repeating radical need not be the same as the preceding one. The

radical may be illustrated by the following groups:

20 and

25 R_2 and R_4 in the above formula may be hydrogen, a lower alkyl group, a lower alkylene-COOB group, or a —COOB group. R_1 and R_3 are lower alkylene groups such as methylene or a lower alkylene group having an additional free bond; R_6 and R_7 are lower alkylene groups such as methylene. R_8 and R_9 may be hydrogen, a lower alkyl radical, or a lower alkylene-COOB radical. B may be the same or different radical from the group consisting of hydrogen, an organic base radical such as triethanolamine, an inorganic base radical such as sodium, or a

30 lower alkyl ester radical such as $—\text{CH}_2\text{—CH}_3$.

40 Products of the above formulae may be produced by reacting an organic poly primary amine with one mole of an alkali metal or tertiary amine salt of an unsaturated polycarboxylic acid for each primary amine group present

45 in the organic poly primary amine. The adduction reaction involves a reaction between the nitrogen atoms of the amine and the double bond of the acid, ester, or salt thereof. This reaction may be illustrated by the following equation:

55 where R_1 and R_2 are hydrogen or lower alkyl groups and R_5 and B are as defined above. The salts formed in this manner may be converted to the free amino acids by treatment with stronger acids. In most cases the free amino acid is precipitated and may be separated by filtra-

60 65

tion. In some instances where the free amino acid is soluble it may be separated by ion exchange methods.

As another illustration of our adduction reaction, itaconic acid may be reacted with triethanolamine to form a salt and the salt may be then reacted with p,p'-methylenedianiline to form p,p'-di-N-pyrrolidone-2,4-carboxylic acid. This reaction is shown below:

Obviously, mixed or unsymmetrical amino acid products may be produced by employing mixtures of different unsaturated polycarboxylic starting materials.

The unsaturated polycarboxylic acids which are suitable for use in producing the compounds of this invention include aconitic, citraconic, itaconic, maleic, fumaric, methylitaconic, glutacaconic, methylglutaconic, muconic acids, and the like, their salts, anhydrides, nitriles, etc. These acids are characterized by the presence of the 1,4 conjugated moiety:

Suitable organic poly primary amines include ethylenediamine, diethylenetriamine, tetraethylenepentamine, propylenediamine, hexamethylenediamine, beta hydroxypropylenediamine, 2,2'-diaminodiethyl ether, 2,2'-diaminodiethyl sulfide, phenylenediamines, 2,2',2'-triaminotriethylamine, benzidine, diaminocyclohexane, diaminophenyl, polygylcoldiamine, lysine, ornithin, methylenedianiline, 0-aminoethyl aniline, ammeline, melamine, tris-3-amino propylamine, etc.

Our novel process for the preparation of the adduction products of the present invention is accomplished by heating a basic aqueous solution or melt of the poly primary amine with the unsaturated polycarboxylic acid for a period of time sufficient to complete the reaction (from a few hours to a few days). The molecular proportions of the reactants are approximately one mole of the unsaturated polycarboxylic acid per primary amine group present in the poly primary amine. The alkalinity of the reaction mixture is established and maintained by means of a strong inorganic base or nonreactive strong organic base. Suitable bases include NaOH, KOH, triethylamine, triethanolamine, and the like. The basicity of the reaction mixture is preferably held at a pH above 9.5. The speed of the reaction may be varied to some extent by varying the temperature and pressure conditions under which the reaction is carried out. In general, the most satisfactory procedure is to heat the mixture to a refluxing temperature at atmospheric pressure for a period of at least several hours. It is essential to maintain alkaline reaction conditions during such polyadduction reactions in order to prevent unnecessary complex side reactions involving carboxylic hydrogens with excess amine groups.

The following typical examples illustrate the general nature of the new process and show a variety of bis-adducts of diprimary amines with unsaturated polycarboxylic acids.

EXAMPLE I

Ethylenediamine Bis-N,N'-Succinic Acid

400 grams of maleic anhydride (4.1 moles) were added to 400 ml. water, and the mixture was set aside for one hour. This mixture was neutralized slowly under a reflux condenser, while cooling (75-85° C.) and stirring during the dropwise addition of 700 g. of 50% by weight NaOH (8.75 moles). Extreme caution should be exercised at this stage, since if NaOH accumulates in quantity unreacted in the reaction media, it may suddenly react with near-explosive violence. However, during this neutralization-hydrolysis, the temperature should not be allowed to drop below 70° C. in order to prevent the separation of sodium maleate.

The hot reaction solution of disodium maleate was treated with 170 g. of 70% by weight ethylenediamine (2.0 moles). The solution was then digested above 95° C., and finally treated under reflux for 48 hours in a stainless steel reactor. The final reaction solution (36° Bé.) was cooled to room temperature, then acidified to a pH of 2.0 with 680 ml. of concentrated HCl (8.2 moles). When no further product separates (6-16 hours), the white slurry of micro-crystals was filtered, washed with three, 250 ml. portions of water, and then dried to a constant weight at 90-100° C. The products melted at 220-222° C. and constituted 540 g. yield (92.2% of the theoretical 548 g. yield).

The product, ethylenediamine bis-N,N'-succinic acid (EDDS-4H), was found to be only slightly soluble in water and insoluble in ethanol, acetone, benzene, and most organic solvents. 0.77 gram of the product dissolved in 100 ml. of H₂O at 28° C.

A 292 g. (1.0 mole) portion of EDDS-4H was dissolved in 400 ml. of water containing 160 g. (4.0 moles) of NaOH. The solution was cooled, and acidified to a pH of 2.0 with 330 ml. of concentrated HCl (4.0 moles). The solution was seeded, and was set aside (undisturbed) for 24 hours, filtered, and then washed with 500 ml. of water. The product was air dried to the dihydrate. Recrystallization yielded 280 g., that is, 85.4% of the theoretical yield of 328 g. The product was divided into two portions: (A), which was analyzed as such and (B), which was dried to a constant weight at 90° C. A pentahydrate of EDDS-4H was prepared by passing boiling water through a pad of EDDS-4H; rapid cooling of the clear filtrate yielded long, transparent needles (C). Analytical data have confirmed the samples as:

- (A) EDDS-4H·2H₂O
- (B) EDDS-4H, anhydrous
- (C) EDDS-4H·5H₂O

65 Molecular weight determined by pH titration:

- (B) C₁₀H₁₆N₂O₈: found 290, theory 292; inflections at pH of 5.5, 8.7 and 11.25.
- (C) C₁₀H₁₆N₂O₈·5H₂O: found 383, theory 382; inflections at pH of 5.5, 8.7 and 11.25.

Total N values determined by Kjeldahl:

- (B) C₁₀H₁₆N₂O₈, percent N: found was 9.51; theory 9.59.
- (C) C₁₀H₁₆N₂O₈·5H₂O, percent N: found was 7.34; theory 7.33.

A 269.5 g. sample of EDDS-4H·2H₂O (0.8216 mole) was dried at 95° C. to a constant weight. The 28.5 g. (1.583 moles) loss of water corresponds to the theoretical loss from the dihydrate.

The reactions were usually carried out in metal reactors, preferably stainless steel, in order to avoid contamination by glassware. The conditions described were designed from the viewpoint of simplicity, economy, and convenience, but departure from these conditions may be tolerated without detrimental effects.

The quantity of solvent water, time of reaction, pH of precipitation, and total time of precipitation may all be varied, somewhat, without any serious drop in product yield.

The rate of formation of EDDS-4H by the procedure described in Example I was determined by periodic isolation of product during the over-all reaction time. Table I below shows the quantity of product which approaches a maximum value:

Time of reaction (hrs.):	Percent yield
1.5	55.1
3	67.9
5	71.8
8	76.2
24	85.1
32	87.2
48	89.7

When the yield of EDDS-4H is plotted against the log of the reaction time, a straight line is obtained. Extrapolation to 100% yield shows the obtaining of the theoretical yield after 155 hours of refluxing.

The true amphoteric nature of these polyamino poly-carboxylic acids is shown by their ability to form salts with mineral acids.

EXAMPLE II

Ethylenediamine Bis-N,N'-Succinic Acid Dihydrogen Sulfate

40 grams of ethylenediamine bis-N,N'-succinic acid (0.144 mole) were added to 100 g. of 98% sulfuric acid. The mixture was kept below 30° C. in an ice bath and stirred so as to form a solution. The solution, when diluted at room temperature with 100 ml. of H₂O, formed a white microcrystalline precipitate. The product was collected on a sintered glass funnel, and then dried several days in a vacuum desiccator. A yield of 30 g. was obtained.

Analytical data.—C₁₀H₁₈N₂O₁₂S, percent N: found 6.86; theory 7.18. Molecular weight determined by pH titration: found 391; theory 392; inflections at pH of 3.0, 5.5, 8.5 and 11.25.

EXAMPLE III

Ethylenediamine Bis-N,N'-Succinic Acid Dihydrochloride

30 grams of ethylenediamine bis-N,N'-succinic acid were added, with stirring, into 100 ml. of concentrated hydrochloric acid at room temperature to form a solution. After several minutes, a fine white crystalline precipitate

separated out. The precipitate was filtered, washed with three, 25 ml. portions of acetone, and vacuum desiccated for several days. The yield was 28 g.

Analytical data.—C₁₀H₁₈N₂O₈Cl₂, percent N: found 7.36; theory 7.67. Molecular weight determined by titration: found 373; theory 365; inflections at pH of 5.5, 8.5 and 11.25.

Ethylenediamine bis-N,N'-succinic acid may easily be converted to an ester as shown.

15 A 146 g. (0.5 mole) sample of EDDS-4H in 400 ml. of ethanol was treated dropwise with 80 g. of concentrated H₂SO₄. The admixture was refluxed for 7 hours (a solution was formed after 4 hours). The clear liquor was diluted with ethanol, at 20° C., to 750 ml. and 168 g. (2 moles) of NaHCO₃ were added thereto. The slurry was filtered and washed with 100 ml. of ethanol. The combined liquor was again filtered with norite carbon and concentrated in vacuo at 80° C. The viscous, straw-colored syrup was soluble in water, alcohol, and acetone. 20 The yield was 200 g. of crude product, which is 99% of theoretical yield of 202 g.

25 In addition to forming salts with acids, these amphoteric amino acids also form crystalline salts with suitable bases. The disodium dihydrogen salt forms a crystalline product; however, the tetrasodium salt is extremely soluble and hygroscopic.

EXAMPLE IV

Disodium Ethylenediamine Bis-N,N'-Succinate

35 86.9 grams of ethylenediamine bis-N,N'-succinic acid (0.3 mole) were added to 50 ml. of water, then dissolved by the addition of 59.2 ml. of 10.07 N NaOH (0.6 mole). The slurry was heated to form a solution, which was allowed to cool slowly. The product was filtered as dry as possible in vacuum. The white crystalline product was recrystallized from 200 ml. of water. The yield was 32.6 g., 32% of the theoretical 100.9 g. (anhydrous) yield.

40 One-half of the above product was dried at 90° C. and was analyzed.

45 *Analytical data.*—C₁₀H₁₄N₂O₈Na₂·4H₂O, percent N: found 6.71; theory 6.81. C₁₀H₁₄N₂O₈Na₂, percent N: found 8.13; theory 8.33. Molecular weight by pH titration: EDDS-2Na-4H₂O, M.W.: found 411; M.W.: theory 408. EDDS-2Na, M.W.: found 342; M.W.: theory 336.

EXAMPLE V

65 70 89.6 grams of ethylenediamine bis-N,N'-succinic acid (0.307 mole) were added to 50 ml. of water, then dissolved with 40 ml. of concentrated NH₄OH (29% by weight NH₃) while stirring and heating. When the solution was cooled to 0° C., a large crop of white crystals formed. These crystals were filtered, washed with 4 ml. of water and filtered dry on a Buchner funnel. The

product was air dried to a constant weight. The product weighed 65.6 g., 65.6% of the theoretical 100 g. yield.

Analytical data.— $C_{10}H_{22}N_4O_8 \cdot 2H_2O$, total percent N: found 15.27; theory 15.47. Percent N as free NH_3 : found 7.56; theory 7.73.

While ethylenediamine bis-N,N'-succinic acid has been found to be stable in boiling alkaline or neutral solutions, prolonged boiling at its isoelectric point does result in a change.

The preparation of ethylenediamine bis-N,N'-succinic acid is not limited to the use of maleic acid as the starting material. With little modification, the trans isomer, fumaric acid is easily substituted.

EXAMPLE VI

Ethylenediamine Bis-N,N'-Succinic Acid (EDDS-4H)

232 grams of fumaric acid (2.0 moles) were added to 200 ml. of water, and the mixture was stirred. 320 grams of 50% by weight of NaOH (4.0 moles) were added to the reaction mixture. Again, the exothermic reaction required moderate cooling ($80^\circ C.$), a reflux condenser, and good agitation. The reaction suspension was treated with 70 g. (86% by weight) of ethylenediamine (1.0 mole) diluted with 300 ml. of water, and was refluxed 56 hours. The partially soluble disodium fumarate gradually dissolved as it was consumed in the reaction.

The final clear reaction solution was cooled, then acidified to a pH of 2.0 with 360 ml. of concentrated HCl. When no further product separated from the solution (8–16 hours), it was filtered, washed with several portions of water, and dried to a constant weight at $100^\circ C.$

89.6 grams of ethylenediamine bis-N,N'-succinic acid C. Yield: 220 g., 75% of theory (292 g.); M.P.: 220–222° C. (M.P. of EDDS-4H; 220–222° C.).

The melting point of this product was not changed when admixed with the crystalline product of Example I, which identifies the product made with fumaric acid as being the same as that made with maleic acid.

While KOH may be freely substituted for NaOH in the preparative procedure of EDDS-4H, a volatile tertiary amine such as triethylamine can be used with some reservation. The lower boiling point of this amine lowers the reflux temperature, and cuts the yield to a less favorable 32%. A higher boiling amine such as triethanolamine will be shown to be a favorable substitute for NaOH.

Attempts to react the secondary nitrogen of EDDS-4H with additional maleic groups were not successful under the mild conditions of Example I.

EXAMPLE VII

Diethylenetriamine Bis-N,N'-Succinic Acid

Ethylenediamine is only the first in a varied series of polyamines that yield insoluble adducts with maleic acid.

Repeating the conditions of Example I, diethylenetriamine was substituted for ethylenediamine, as is described in the following example.

5 The reaction was carried out as described in Example I, combining 200 g. of maleic anhydride (2.02 moles) in 100 ml. of water with 320 g. of 50% by weight NaOH. This solution was then treated with 103 g. of diethylenetriamine (1.0 mole) and was refluxed for 48 hours. The reaction mixture had to be diluted to 800 ml. during the reflux period so as to keep the reactants and product in solution.

10 The reaction solution was cooled and then acidified with 320 ml. of concentrated HCl to a pH of 3.3. Upon setting overnight, the product, a fine white microcrystalline product, was filtered and washed with two, 100 ml. portions of water. This material was dried at $100-105^\circ C.$ to a white free-flowing powder. Yield: 180 g., 57% of theory (335 g.); M.P.: 208–210° C.

15 The sample of diethylenetriamine bis-N,N'-succinic acid was recrystallized in the normal manner, that is, by dissolving it first in NaOH solution, followed by reprecipitation in the cold at a pH of 3.3 with concentrated HCl. The resulting product was filtered and washed thoroughly with water. The product was divided into fraction (A) which was air dried to a constant weight and fraction (B) which was dried at $100^\circ C.$ to a constant weight.

Analytical data:

20 (A) $C_{12}H_{21}N_3O_8 \cdot H_2O$, M.W. determined by pH titration: found 358, theory 353; percent N found: 11.72, theory 11.90.
 (B) $C_{12}H_{21}N_3O_8$, M.W. determined by pH titration: found 340, theory 335; percent N found: 12.49, theory 12.54.

25 The series of polyethylene polyamines was continued with the next member, triethylenetetramine. Since the product is water soluble, a modification in procedure for isolating the product was required.

EXAMPLE VIII

Triethylenetetramine Bis-N,N'''-Succinic Acid

30 The reaction was carried out in the same manner described in Example I, that is, by combining 200 g. of maleic anhydride (2.04 moles) in 100 ml. of H_2O with 320 g. of 50% by weight NaOH. The solution was treated with 146 g. of triethylenetetramine (1.0 mole) and was refluxed for 48 hours.

35 The reaction solution was filtered, cooled, and diluted to 1 liter. This corresponds to a 1 molar solution of tetrasodium triethylenetetramine bis-N,N'''-succinate. A 100 ml. (0.1 mole) aliquot was acidified with 25 ml. of concentrated HCl, but did not yield any precipitate.

40 Another 100 ml. (0.1 mole) aliquot of the tetrasodium salt was passed through Amberlite IR-100 cation exchange resin (acid form). The 800 ml. of acidic effluent were concentrated under vacuo to a syrup. The syrup was further dried by washing with ethanol, and desiccation for several weeks. The brown product hardened to a friable brown solid. This brown solid was insoluble

dried in a vacuum oven at 90° C. The mass foams to a large volume, and then solidifies to a friable mass. The 290 g. yield is 90% of the theoretical yield of 322 g.

A 10 g. sample was recrystallized by mixing with 25 ml. of warm water, cooling to room temperature, seeding, and setting the sample aside overnight. The resulting white crystals were filtered and dried to constant weight at 100° C.

Analytical data.— $C_{11}H_{18}N_2O_9$, percent N: found 8.55; theory 8.69. M.W. determined by pH titration: found 10 334, theory 322. Inflections at pH of 6.0 and 11.0.

EXAMPLE XII

Barium Dihydrogen Ethylenediamine Bis-N,N'-Succinate

The barium dihydrogen salt is readily obtained from an aqueous solution.

29.2 g. of ethylenediamine bis-N,N'-succinic acid (0.1 mole) were dissolved in 200 ml. of H_2O containing 8 g. of NaOH (0.2 mole). The solution was stirred and rapidly treated with 100 ml. of 1.0 molar BaCl_2 (0.1 mole). The insoluble salt separated after a short period. After settling for 1 hour, the mass was filtered, washed with 100 ml. of water and dried at 110° C. to a constant weight. The 40 g. yield was 93.5% of the theoretical 42.7 g. yield.

Analytical data.— $C_{10}H_{14}N_2O_8\text{Ba}$, percent N: found 6.44; theory 6.56.

A lead dihydrogen salt was similarly prepared from lead acetate solution and ethylenediamine-N,N'-bis-succinic acid.

Aconitic acid was utilized in order to show the adaptability of unsaturated tricarboxylic acids to this process. 40

The substitution of triethanolamine for NaOH as neutralizing base is also described in the following example.

EXAMPLE XIII

Diethylenetriamine Bis-N,N'-Tricarballylic Acid

174 grams of aconitic acid (1.0 mole) were treated with 40 ml. of water, followed by 450 g. (3.0 moles) of triethanolamine (TEA) and, finally, 58 g. (0.5 mole) of hexamethylenediamine. This mixture was then set to digest under gentle reflux at 125–130° C. for 36 hours.

The reaction solution, a dark red-brown syrup, was diluted to 1 liter and was used as a 0.5 molar solution of the product.

A 200 ml. (0.1 mole) aliquot of the reaction solution were treated with 24 g. (0.6 mole) of NaOH and 1 liter of ethanol. Prolonged stirring gave a thick oily sediment of hexasodium salt, which was washed free of triethanolamine with two, 50 ml. portions of ethanol and was dissolved in 200 ml. of water. This solution was

passed through a column of Amberlite IR-100 cation exchange resin (acid form). The acidic effluent was concentrated under vacuo to 65 ml., then treated with 800 ml. of ethanol. A brown solid separated, which was dried in a vacuum desiccator. The yield was 8 g., 21% of theoretical 33.8 g. yield. Its decomposition point was approximately 230° C.

Analytical data.— $C_{16}H_{25}N_2O_{12}$, percent N: found 10.91; theory 9.31. M.W. determined by pH titration: found 447; theory 451. Inflections at pH of 6.8 and 10.5.

The position of adduction of the primary amine to the unsaturation of aconitic acid may be either α or β . Possibly the beta isomer may predominate.

EXAMPLE XIV

Hexamethylenediamine Bis-N,N'-Tricarballylic Acid

174 grams of aconitic acid (1.0 mole) were treated with 40 ml. of water, followed by 450 g. (3.0 moles) of triethanolamine (TEA) and, finally, 58 g. (0.5 mole) of hexamethylenediamine. This mixture was then set to digest under gentle reflux at 125–130° C. for 36 hours.

The reaction mixture, a dark red-brown syrup, was diluted with water to 1 liter and was used as a 0.5 molar solution. Acidification of a sample of this solution precipitates the free acid as an oil; however, it is quite unstable in air and soon auto-oxidizes to a black resinous mass. Thus, it was considered more feasible to prepare one of its metal salts, in this case, the trizinc salt.

EXAMPLE XV

A 100 ml. (0.05 mole) aliquot of the above reaction solution of Example XIV was diluted with 100 ml. of water. The solution was then treated, while stirring, with 150 ml. of 1 molar ZnCl_2 solution. The reaction mixture had a pH of 7.3. The product was filtered, was sequentially washed with 200 ml. of water and 100 ml. of ethanol, and was then dried to a constant weight at 125–130° C. The yield was 20 g., 63% of the theoretical 32.5 g. yield.

Analytical data on Zn_3 salt.— $C_{18}H_{22}N_2O_{12}\text{Zn}_3$, percent N: found 4.06; theory 4.28.

The reactivity of aliphatic primary amines has been conclusively shown in the previous examples. The next step incorporated aromatic polyamines into our process. The expected difficulty was encountered with these adducts, that being the tendency of the free amino acids to oxidize in open air. Because of this, the adduct was identified after conversion to a suitable metal salt.

EXAMPLE XVI

*p,p'-Methylenedianiline Bis-N,N'-Succinic Acid*The aryl amine incorporated into this reaction is water insoluble, as well as being insoluble in any alkaline aqueous media. Thus, triethanolamine was again used as both solvent and neutralizing base.

100 grams of maleic anhydride (1.02 moles) were added to 25 ml. of water and allowed to hydrolyze slowly to maleic acid. The mass of crystals were gradually dissolved in 330 g. (2.2 moles) of triethanolamine. Finally, 99 g. (0.5 mole) of *p,p'*-methylenedianiline were added and the reaction mixture digested under reflux at 130-140° C. for 26 hours. The reaction solution remained as one clear phase.

The solution was cooled and diluted with 250 ml. of water. Since the reaction solution remains as one phase, this is evidence that the amine has reacted, otherwise it would have separated on dilution.

The diluted solution was acidified with 183 ml. of concentrated HCl (2.2 moles). A gray oil separated immediately and was decanted free of the mother liquor. This residue was washed with 200 ml. of water, dissolved in 280 ml. of water containing 80 g. (2.0 moles) of NaOH, and reprecipitated with 166 ml. of concentrated HCl (2.0 moles). The residue was again decanted free of mother liquor, washed with three, 200 ml. portions of water and two, 150 ml. portions of ethanol. The free acid solidified when desiccated; however, the surfaces turned red when exposed to air, evidencing oxidation. The yield was 150 g., 70% of the theoretical 215 g. yield.

*Dizinc p,p'-Methylenedianiline Bis-N,N'-Succinate*43 grams of *p,p'*-methylenedianiline bis-N,N'-succinic acid (0.1 mole) were dissolved in 120 g. of water containing 16 g. (0.4 mole) of NaOH. The solution was filtered with Norite carbon and was then treated while stirring with 200 ml. of 1 molar $ZnCl_2$ solution for 1 hour. The zinc salt separated out immediately during stirring. The product was filtered, and was washed thoroughly with three, 50 ml. portions of water, followed by 50 ml. of ethanol. The gray-white microcrystalline product was dried to constant weight at 105-110° C.

Analytical data. — $C_{21}H_{18}N_2O_8Zn_2$, percent N: found 5.33; theory 5.03.

The following example, which incorporates an aromatic polyamine with another type of unsaturated acid, displays a phenomenon which occurs when the resultant secondary amine is γ to a carboxyl group. An intramolecular cyclization takes place upon acidification, resulting in a pyrrolidone derivative.

EXAMPLE XVII

*Diphenylmethane p,p'-Di-N-Pyrrolidone-2,4-Carboxylic Acid*20 120 grams of itaconic acid (0.92 mole) were added to 10 ml. of water, and the resulting salt was treated with 300 g. of triethanolamine (2.0 moles). The slurry was heated and stirred until completely dissolved. The resultant viscous solution was treated with 91 g. of *p,p'*-methylenedianiline (0.46 mole) and digested under gentle reflux at 120-130° C. for 48 hours. The reaction mixture, which contained some insolubles, was diluted to 600 ml., and filtered through a pad of diatomaceous earth. The clear filtrate was then acidified with 165 ml. of concentrated HCl. The oil, which separated, was decanted free of mother liquor, washed with two, 100 ml. portions of water, and was then redissolved in 250 ml. of water containing 80 g. (2.0 moles) of NaOH. The product was reprecipitated with 165 ml. of concentrated HCl (2.0 moles) washed with two, 100 ml. portions of water, and was then dried in a vacuum desiccator for several days. The final product was a dark-brown crystalline mass. The yield was 40 g., 21% of the theoretical 194 g. yield. The melting point was 200-210° C.

Analytical data. — $C_{23}H_{22}N_2O_6$, percent N: found 6.92; theory 6.64. M.W. determined by pH titration: found 458; theory 422. Inflections at pH of 9.0.

EXAMPLE XVIII

 *α,α' -Diamino, m-Xylene-N,N'-Disuccinic Acid*45 The reaction was carried out as described in Example I, that is, combining 100 g. of maleic anhydride (1.02 moles) in 200 ml. of water with 160 g. (50% by weight) of NaOH. This solution was then treated with 68 g. (0.5 mole) of α,α' -diamino, m-xylene (Oronite MXDA). The reaction mixture was refluxed in a stainless steel vessel for 72 hours, cooled, and filtered. The product (free acid) was water soluble and adheres to an acid ion-exchange resin. The product was isolated with the di-calcium salt.

The above reaction liquor was treated while stirring with 111 g. (1.0 mole) of calcium chloride dissolved in 1 liter of water. The slurry was stirred for 2 hours, filtered, and washed with 500 ml. of water and 100 ml. of ethanol. The white microcrystalline product was oven dried at 100° C. to a constant weight. The yield was 211 g., 95% of the theoretical 222 g. yield.

Analytical data. — $C_{16}H_{16}N_2O_8Ca_2$, percent N: found 6.60; theory 6.31.

The dicalcium salt was readily converted to the free acid with oxalic acid.

210 grams of the dicalcium salt (0.95 mole) were slurried with 1 liter of water. The 120 g. of oxalic acid dihydrate (0.96 mole) were added and stirred therewith for 5 hours. The white slurry was filtered, and washed with 300 ml. of water. The combined mother liquor and washings were then evaporated to 400 ml. (at room temperature). The residual syrup was treated with 500 ml. of acetone. The oily residue was then washed with two, 500 ml. portions of acetone and a 500 ml. portion of ethanol. The final semi-solid was dried in a vacuum oven at 90° C.; it foamed. The friable mass was crushed and further dried to constant weight. The over-all product, a pale yellow mass, was water soluble and non-hygroscopic. The melting point was 155° C.

Analytical data. — $C_{16}H_{20}N_2O_8$, percent N: found 7.79; theory 7.61. M.W. determined by pH titration: found 362; theory 368. Inflections at pH of 6.5 and 11.25.

The series of amino acids which may be obtained from the union of poly primary amines with unsaturated poly-carboxylic acids can be seen as nearly limitless. The examples shown are intended to illustrate our invention and should not be interpreted as limiting it.

The utilization of the products of our process are varied and numerous. Many of its outstanding uses are based upon its unique properties as a chelating compound. Some of the ions successfully tested are shown below. In the test, a 15 ml. sample of 0.1 molar chelate was added to 50 ml. of water treated with 10 ml. of 0.1 molar of the metal ion and 1 ml. of precipitant such as saturated Na_2HPO_4 or oxalic acid. The solution was adjusted to the recorded pH. The solution was studied in the cold for 1 hour and was then boiled. All solutions below remained clear throughout.

TABLE II

Chelate Compd. *	Examples	Ions Chelated	pH Range
EDDS-4H	I.....	Fe ⁺⁺ , Fe ⁺⁺⁺ , Cu ⁺⁺ , Mn ⁺⁺ , Zn ⁺⁺ .	4-8

*Identified by initials assigned to formulas in the various examples.

The chelates of the amino acids were in some cases quite easily prepared in a pure form. The procedure below may be used for many of the amino acids, and many metal ions.

EXAMPLE XIX

Cupric Dihydrogen Ethylenediamine Bis-N,N'-Succinate

29.2 grams of ethylenediamine bis-N,N'-succinic acid, 35 EDDDS-4H (0.1 mole) were mixed with 25 ml. of water that was treated with 20 g. of cupric acetate monohydrate (0.1 mole). The admixture was warmed and stirred to form a solution. When the blue liquor was diluted with 200 ml. of ethanol, the water soluble cupric chelate of ethylenediamine bis-N,N'-succinic acid separated out. 40 This was filtered and dried to provide a nearly quantitative yield of the product. Recrystallization of the product from water and ethanol yielded a purified product.

The crystalline manganous dihydrogen chelate of 45 EDDDS was prepared analogously except that 24.5 g. of manganous acetate tetrahydrate was used instead of 20 g. of cupric acetate monohydrate.

Analytical data. — $Cu^{II}H_2$ chelate (from $Cu(C_2H_3O_2)_2$): $C_{10}H_{14}N_2O_8Cu$; percent N: found 7.82; theory 7.90. $Mn^{II}H_2$ chelate (from $Mn(C_2H_3O_2)_2$): $C_{10}H_{14}N_2O_8Mn$; percent N: found 7.58; theory 8.12.

These and other metal chelates of the new bis-adducts of this invention are relatively soluble in water and have utility as a source of normally insoluble metal compounds in soluble form. As such they may be used as sources of trace elements in fertilizer mixtures, insecticide formulas, etc.

EXAMPLE XX

The new bis-adduct compound described in the above examples have been found to be quite effective in removing rust and oxide coatings from metal surfaces at pH values below about 9.0 in aqueous solutions containing a reducing agent such as a sulfite, hyposulfite, sugar hydroquinone, etc. For example, uniformly rusted iron (aged) strips were immersed for three hours (without agitation) at 75° C. in a cleaning solution having the formula:

Bis-adduct compound _____ grams 15.0
Sodium bisulfite (58.5% SO_2) _____ do 7.5
Water, sufficient amount to form a 300.0 ml. soln.

The pH of the solution was adjusted to 8.0 with NaOH.

The weight of the rust lost from the 81.6 sq. cm. surface of the metal strips and the condition of the resulting metal surfaces were noted as follows.

TABLE III

Examples	Compounds	Wt. of Rust Lost (g.)	Results
I	$\left[\begin{array}{c} \text{H} \\ \\ \text{CH}_2\text{N}-\text{CHCOOH} \\ \\ \text{CH}_2\text{COOH} \end{array} \right]_2$	0.589	Clean surface, few rust spots.
VII	$\text{HN}-\left[\begin{array}{c} \text{H} \\ \\ \text{CH}_2\text{CH}_2\text{N}-\text{CHCOOH} \\ \\ \text{CH}_2\text{COOH} \end{array} \right]_2$	0.697	Do.
VIII	$\left[\begin{array}{c} \text{H} \quad \text{H} \\ \quad \\ \text{CH}_2\text{N}-\text{CH}_2\text{CH}_2\text{N}-\text{CHCOOH} \\ \\ \text{CH}_2\text{COOH} \end{array} \right]_2$	0.072	Do.
IX	$\text{HN}-\left[\begin{array}{c} \text{H} \quad \text{H} \\ \quad \\ \text{CH}_2\text{CH}_2-\text{NCH}_2\text{CH}_2\text{N}-\text{CHCOOH} \\ \\ \text{CH}_2\text{COOH} \end{array} \right]_2$	0.754	Clean.
X	$\left[\begin{array}{c} \text{H} \\ \\ \text{CH}_2\text{CH}_2\text{CH}_2\text{N}-\text{CHCOOH} \\ \\ \text{CH}_2\text{COOH} \end{array} \right]_2$	0.028	Much rust remains.
XI	$\text{HOCH}-\left[\begin{array}{c} \text{H} \\ \\ \text{CH}_2\text{N}-\text{CHCOOH} \\ \\ \text{CH}_2\text{COOH} \end{array} \right]_2$	1.017	Clean (rapid action).
XIII	$\text{HN}-\left[\begin{array}{c} \text{H} \quad \text{CH}_2\text{COOH} \\ \quad \\ \text{CH}_2\text{CH}_2\text{N}-\text{C}(\text{COOH})_2 \\ \\ \text{CH}_2\text{COOH} \end{array} \right]_2$	0.060	Spotted rust.
XVIII	$\text{CH}_2\text{N}-\left[\begin{array}{c} \text{H} \\ \\ \text{CH}_2\text{COOH} \\ \\ \text{CH}_2\text{COOH} \end{array} \right]_2$	0.537	Do.
Blank		0.0343	Rusty.

When the test strips were freshly rusted (36 hours) with a 5% NH_4Cl solution, the removal of rust was much

rapid and complete. Under the same conditions the results are tabulated below.

TABLE IV

Examples	Compounds	Wt. of Rust Lost (g.)	Results
I	$\left[\begin{array}{c} \text{H} \\ \\ \text{CH}_2\text{N}-\text{CHCOOH} \\ \\ \text{CH}_2\text{COOH} \end{array} \right]_2$	1.249	Clean.
VII	$\text{HN}-\left[\begin{array}{c} \text{H} \\ \\ \text{CH}_2\text{CH}_2\text{N}-\text{CHCOOH} \\ \\ \text{CH}_2\text{COOH} \end{array} \right]_2$	0.911	Spotted rust (rinsed off).
VIII	$\left[\begin{array}{c} \text{H} \quad \text{H} \\ \quad \\ \text{CH}_2\text{N}-\text{CH}_2\text{CH}_2\text{N}-\text{CHCOOH} \\ \\ \text{CH}_2\text{COOH} \end{array} \right]_2$	1.157	Clean.
IX	$\text{HN}-\left[\begin{array}{c} \text{H} \quad \text{H} \\ \quad \\ \text{CH}_2\text{CH}_2-\text{NCH}_2\text{CH}_2\text{N}-\text{CHCOOH} \\ \\ \text{CH}_2\text{COOH} \end{array} \right]_2$	0.992	Do.
X	$\left[\begin{array}{c} \text{H} \\ \\ \text{CH}_2\text{CH}_2\text{CH}_2\text{N}-\text{CHCOOH} \\ \\ \text{CH}_2\text{COOH} \end{array} \right]_2$	0.579	Large rust spots.
XI	$\text{HOCH}-\left[\begin{array}{c} \text{H} \\ \\ \text{CH}_2\text{N}-\text{CHCOOH} \\ \\ \text{CH}_2\text{COOH} \end{array} \right]_2$	1.281	Clean (rapid action).

TABLE IV—Continued

Examples	Compounds	Wt. of Rust Lost (g.)	Results
XIII		0.105	Rusty.
XVIII		0.763	Clean.

The above compounds show excellent rust removal capability.

The addition of the above adduct amino acids to alkaline solutions, such as sodium carbonate or phosphate, speeds the cleaning or etching of aluminum. Test solutions were prepared containing the following ingredients:

Amino acid g. 4
 Trisodium phosphate, crystal g. 2
 Water, sufficient amount to form a 200 ml. soln.

20 The pH of the solution was adjusted to 11.5 with NaOH at 60° C.

A Reynolds 3S-H-14 aluminum test strip of 30.1 sq. cm. surface area was immersed in each solution for 1/2 hour. The results are tabulated below.

25 The addition of the new adduct acid compounds to solutions of strong mineral acids was found to greatly decrease the acid attack on plain iron. 0.5%, 1.0% and 3% (by weight) samples in 75% H₃PO₄ at 30° C. were tested on a 7.6 x 4.5 x 0.5 cm. strip of iron for five hours. The following results were produced.

TABLE V

Examples	Compounds	Wt. of Al. Lost (g.) 1/2 hr.	I.P.Y.
I		0.101	8.14
VII		0.0965	7.73
VIII		0.118	9.47
IX		0.055	4.42
X		0.038	3.01
XI		0.095	7.59
XIII		0.077	6.17
XVIII		0.044	3.53
Blank		0.026	2.08

*When the solutions were later lowered to a pH 8.5, they all deposited a white floc except the 2-hydroxypropylene-1,3-diamine bis-N,N'-succinic acid, which displays its superior sequestration of aluminum.

TABLE VI

Examples	Compounds	Steel Lost (g.)		
		0.5%	1.0%	3.0%

Blank		0.198	—	—

The results which are underlined represent data from solutions where the added adduct acid was incompletely dissolved.

EXAMPLE XXI

The soap-acid amines form amides with EDDS-adducts to yield compounds of interest. Armeen OD, a mixture of high molecular weight amines (Armour and Co.) with oleyl amine predominatory, was fused with ethylenediamine bis-N,N'-succinic acid.

53 grams of Armeen OD (0.2 mole) were treated with 29.2 g. of ethylenediamine bis-N,N'-succinic acid (0.1 mole). The mixture was warmed slowly with stirring to 160° C. and kept at this temperature (under a short, air condenser) for one hour. The liquor was cooled, dissolved in 250 ml. of ethanol, and was filtered free of insolubles. The liquor was then heated free of ethanol in a vacuum oven at 80° C. The product, a clear brown viscous liquid, weighed 75 g.

The product of this reaction is an effective wetting and foaming agent suitable for use in cleaning and ore flotation operations. In concentrations of less than 0.25%

45 by weight, foams were obtained which were stable for 30 minutes or more. These foams were formed in alkaline (pH of 10), neutral, and acid (pH of 1.5 or less) solutions. Armeen OD itself forms stable foams in acid and neutral solutions, but in alkaline solutions it deposits 50 much insoluble amine.

Similar results were obtained with Armeen CD, and coco oil base amine, the latter also being a product of Armour and Co.

These soap-acid amides are soluble in ethanol, chloroform, benzene and kerosene, but are almost insoluble in water and acetone. One g. of compound was tested with 25 g. of solvent.

EXAMPLE XXII

60 A water-soluble polymer may be prepared by the fusion of ethylenediamine bis-N,N'-succinic acid with urea.

120 grams of urea were melted at 130-140° C. and were then treated in small portions with 146 g. of ethylenediamine bis-N,N'-succinic acid (0.5 mole) while stirring the liquid mass to keep down the foam. When foaming had diminished (after some 2 hours of heating) the heating was discontinued. The clear amber syrup was cooled and thereby hardened to a brittle amber glass. The glass was hygroscopic and water soluble. The residue totaled 244 g., a loss of 22 g.

This product may be incorporated into urea and other resin formulations as a modifier.

A titration curve showed two inflections, at a pH of 6.0 and 11.0. The molecular weight was calculated as 415 g. This corresponds closely to a ratio of one mole of ethylenediamine bis-N,N'-succinic acid to two moles urea molecules. The pH of an aqueous solution of the polymer was found to be 6.92.

Because of their general chelating and metal solubilizing characteristics and the reaction characteristics with other organic compounds the new compounds of this invention may readily suggest themselves for uses not enumerated above.

The foregoing detailed description has been given for clearness of understanding only, and no unnecessary limitations should be understood therefrom, as modifications will be obvious to those skilled in the art.

We claim:

1. A compound selected from the group consisting of:
(a) a compound of the formula:

wherein Z_1 and Z_2 are saturated acyclic bis-adduction groups derived from the class consisting of lower alkenyl, 1,4 conjugated polycarboxylic acids having at least 2 and not more than 3 carboxyl groups, and salts thereof and R_5 is a member of the class consisting of lower alkylene, phenylene-lower alkylene-phenylene-lower alkylene, and

groups;

(b) chelates of the compound of (a) and a polyvalent metal ion; and

(c) esters of the compound of (a) and a lower alkanol.

2. A compound of the formula:

wherein Z_1 and Z_2 are saturated acyclic bis-adduction groups derived from the class consisting of lower alkenyl, 1,4 conjugated polycarboxylic acids having at least 2 and not more than 3 carboxyl groups, and salts thereof and R_5 is a member of the class consisting of lower alkylene-phenylene-lower alkylene-phenylene, lower alkylene-phenylene-lower alkylene, and

groups.

3. The product:

4. The product:

5. The product

15 bis-N,N'-tricarballylic acid.

6. The product:

wherein n is a positive integer of not less than 1 and not more than 2 and R_6 and R_7 are lower alkylene groups when n is 1.

30 7. The product:

40 8. Chelate of a compound of claim 2 and polyvalent metal ion.

9. Ester of a compound of claim 2 and lower alkanol.

10. Metal salt of the product of claim 3.

11. Chelate of the product of claim 3 and polyvalent metal ion.

45 12. Ester of the product of claim 3 and lower alkanol.

13. Metal salt of the product of claim 4.

14. Chelate of the product of claim 4 and polyvalent metal ion.

50 15. Ester of the product of claim 4 and lower alkanol.

16. Metal salt of the product of claim 5.

17. Chelate of the product of claim 5 and polyvalent metal ion.

18. Ester of the product of claim 5 and lower alkanol.

55 19. Metal salt of the product of claim 6.

20. Chelate of the product of claim 6 and polyvalent metal ion.

21. Ester of the product of claim 6 and lower alkanol.

22. Metal salt of the product of claim 7.

60 23. Chelate of the product of claim 7 and polyvalent metal ion.

24. Ester of the product of claim 7 and lower alkanol.

25. The method of producing bis-adduction products comprising reacting an organopolyprimary amine with one mole of a member from the group consisting of lower alkenyl, 1,4 conjugated polycarboxylic acids having at least 2 and not more than 3 carboxyl groups, salts thereof and lower alkyl esters thereof for each primary amine group present in the organopolyprimary amine.

65 70 26. The method of producing bis-adduction products comprising reacting in an alkaline medium an organopolyprimary amine with one mole of a member from the group consisting of lower alkenyl, 1,4 conjugated polycarboxylic acids having at least 2 and not more than 3 carboxyl groups, salts thereof and lower alkyl esters

75

25

thereof for each primary amine group present in the organopolyprimary amine.

27. The method of producing bis-adduction products comprising reacting in an alkaline medium an organopolyprimary amine with one mole of a member from the group consisting of lower alkenyl, 1,4 conjugated polycarboxylic acids having at least 2 and not more than 3 carboxyl groups, salts thereof and lower alkyl esters thereof for each primary amine group present in the organopolyprimary amine, and adding acid to the resulting product to form an acidic bis-adduction product.

28. The method of producing a chelate of a bis-adduction product comprising reacting an organopolyprimary

26

amine with one mole of a member from the group consisting of lower alkenyl, 1,4 conjugated polycarboxylic acids having at least 2 and not more than 3 carboxyl groups, salts thereof and lower alkyl esters thereof for each primary amine group present in the organopolyprimary amine to form a bis-adduction product, and adding a polyvalent metal to said product to form a chelate.
